CARBURETOR VENTURI CONSTRUCTION

Fred A. Kommer, St. Louis, Mo., assignor to
Carter Carburetor Corporation, St. Louis, Mo.,
a corporation of Delaware

Application October 14, 1947, Serial No. 779,757

12 Claims. (Cl. 261—75)

1

This invention relates to carburetors for internal combustion engines, as automotive engines and the like, and has particular reference to the provision of a carburetor fuel nozzle and Venturi section of improved construction and to a novel method of forming the nozzle and Venturi assembly for carburetors of the so-called "low angle nozzle" type.

Carburetors of the type indicated offer certain definite advantages in meeting given carburetor performance characteristics, as is well understood. However, because of the "low angle nozzle" arrangement wherein the fuel nozzle enters the primary Venturi passage at an angle nearly normal to the axis of the Venturi passage, or as otherwise stated, at an angle such that the longitudinal axis of the nozzle in projection across the Venturi passage intersects the Venturi wall opposite the nozzle, certain difficulties have been encountered heretofore in the construction of Venturi sections having the indicated character of nozzle and primary Venturi assembly. The general or prevailing practice is to provide for inserting the nozzle by drilling from the exterior of the section at one side, and in instances where the carburetor body includes the float bowl as a part thereof, this frequently necessitates drilling through a wall or walls of the bowl. Thereafter, the drill openings in the float bowl walls are closed, as by seal plugs. Among the difficulties and disadvantages attending such manner of attaining a low angle nozzle and Venturi arrangement, may be noted the following:

Accurate nozzle passage drilling and seating and positional calibration of the nozzle element are difficult of attainment; the plugged drill openings in the float bowl walls offer zones of possible leakage; and the manufacturing costs are adversely enhanced, in consequence of nozzle passage drilling from the exterior and through the float bowl walls, and the necessary provision of seal plugs in the drill openings.

Accordingly, it is an object of the present invention to provide a carburetor Venturi section affording a low angle nozzle-Venturi assembly wherein the section is characterized by an improved construction such as to avoid the difficulties and disadvantages encountered heretofore in connection with known and prevailing constructions.

Another and equally important object of the invention is to provide a novel and effective method of forming or making a Venturi section having a nozzle-Venturi assembly of the character indicated, whereby the nozzle may be inserted

by way of the primary venturi, and the relationship of the Venturi throat and nozzle tip may be accurately determined.

5 A further object is to provide improvements in the structure of, and method of making, a nozzle Venturi section which will permit of substantial savings in the cost of manufacture.

Other objects and advantages of the invention will appear from the following description thereof and from the accompanying drawing in which:

Fig. 1 is a sectional view vertically through a downdraft carburetor embodying the present improvements.

15 Fig. 2 is a top plan view of the body section of the carburetor further illustrating the invention.

Fig. 3 is an enlarged view, in perspective, of a member providing a wall element which, in assembly of the member to the Venturi section in accordance with the present invention, serves to complete the primary Venturi wall.

20 Fig. 4 is a perspective view illustrating a modified form of the member shown in Fig. 3.

Fig. 5 is a fragmentary view of the Venturi section shown in perspective and illustrating in a 25 position separated from the primary Venturi wall, a modified form of wall element adapted for assembly to the primary Venturi wall to complete the same.

Although not limited to a downdraft carburetor, the invention is here illustrated in application to a carburetor of this type. As appears in Fig. 1, the carburetor shown comprises in superposed assembly, an air horn 10 having a choke valve 11 therein, a Venturi or body section 12 and a throttle body 14 including a throttle valve 15 therein. The throttle body provides a mounting flange 16 by which the carburetor is attached to the intake manifold of an internal combustion engine (not shown). In the present example, the Venturi casting section 12 provides at one side a liquid fuel chamber 18 the upper open end 19 of which is closed by a cover 20 formed as a lateral extension of the air horn 10. Chamber 18 is vented to atmosphere as by a tube 22 preferably extending to the air inlet end of the air horn. Within the fuel chamber is the usual float valve mechanism indicated generally by the numeral 23.

The Venturi section 12 provides therein a Venturi stack affording a primary Venturi passage 24, an intermediate Venturi passage 26 and a main Venturi passage 27, the last being defined by the interior wall 28 of the body section. Venturi passage 26 is defined by a Venturi-forming circular wall 30, while the primary Venturi passage 24 is defined in part by a circular wall 31

hereinafter to be more fully described, the walls 30 and 31 being supported preferably by diametrically opposite webs 32 and 34 integral with the Venturi walls and the casing section. The main fuel system is provided in the Venturi section and includes a vertical passage 35 which receives fuel from the float chamber 18 as through a suitable metering orifice (not shown), and conducts fuel to an inclined passage 36 leading to the primary venturi, the passage 36 extending through the web 34 which is of sufficient thickness to accommodate the passage. In passage 36 is a suitable fuel nozzle element 38 which projects therefrom into the primary Venturi passage 24, the nozzle terminating in a discharge tip 39 near the axis of the Venturi passage. Air is bled to the main fuel system as from the float chamber vent through a passage 40 and a tube 42 having ports 43 opening to the fuel passage 35. Tube 42a constitutes part of the idling system discharging through porting (not shown) adjacent and posterior to the throttle when closed.

As appears from the view of Fig. 1, the nozzle element 38 enters the primary Venturi passage 24 at a relatively low or sharp angle with respect to a horizontal plane through the venturi. The inclination of passage 36 is such that its longitudinal axis intersects the wall of the primary Venturi tube so that the nozzle cannot be inserted from inside the tube without mutilation thereof. Wall element 44 is here provided as a separate part for a purpose presently to be described, and is assembled to the wall 31 in a manner which will appear hereinafter.

Turning now to the present improved method of providing the fuel nozzle and primary Venturi assembly, as shown by Fig. 1, body section 12 is formed, as by casting, to afford the Venturi stack therein wherein the primary Venturi wall 31 is incomplete in its circular extent inwardly of the inlet throat end 45 thereof, to provide a side opening, such as that shown at 46 in Fig. 5, defined by side margins 47 and bottom margin 48 (Figs. 1 and 2). Moreover, in casting the section, web 32 is provided such that it terminates in an upper horizontal end margin 50 a predetermined distance below the upper end 51 of the section while the side opening in wall 31 is disposed in centered relation to and extends above the end 50 of the web. The side opening thus is located diametrically opposite passage 36 drilled into the casting through which the nozzle 38 is to extend. The section, as cast, includes also a lateral extension 54 providing therein a pocket or recess 55 above and adjoining the outer end of the web margin 50, the recess serving a purpose to appear.

In accordance with the present method, passage 36 is drilled from the inner end by extension of a drill over the web margin 50 and through the Venturi wall side opening 46. Nozzle element 38 is then applied through Venturi wall opening 46 and firmly seated in passage 36. The nozzle is retained in place preferably by press-fit thereof in the passage. In so mounting the nozzle, the Venturi passage 24 and wall side opening 46 afford full access to the nozzle, permitting of its adjustment in relation to the primary Venturi passage. Once the nozzle is assembled and adjusted, the wall side opening 46 is closed by the wall element 44 heretofore mentioned, which is shaped in accordance with the Venturi-contouring of the wall 31 in the region of the wall opening 46, whereby the wall 31 is thus completed to afford a full primary Venturi passage.

With reference to Figs. 1, 2, and 3, wall element

44 is provided as an integral part of a pre-formed member comprising a relatively thin stem or fin 60 having the wall element 44 at one end, and a block-like part 61 at its opposite end. The block 61 is provided with a recess or channel 62 extending transversely in its upper surface 64, while the wall 44 is undercut to provide a shouldered bottom margin 65. In assembly to the Venturi section, the preformed member is arranged on the margin 50 of web 32 with the block 61 in the casing recess 55 and the wall 44 in the Venturi wall opening 46. The lower margin 48 of the latter opening is shouldered at 66 to receive the shouldered margin 65 of wall element 44 in lap-fit therewith (Fig. 1), and the dimensions of the wall element 44 with respect to the opening 46 are predetermined such as to afford substantially a press-fit of the wall element in the opening. Once in place, the preformed member is securely locked in assembly to the Venturi casing section as by staking or peening marginal portions 68 (Fig. 2) of the casing at the recess 55, into the block channel 62 at the opposite ends of the latter. It is to be noted that the fin 60 is of a thickness corresponding to that of the web 32, so that the fin in effect is an upward extension of the web, completing the latter to the top end of the Venturi casing section.

Fig. 4 illustrates a modification of the pre-formed member shown in Fig. 3, the difference residing in the partial undercutting of the side margins 70 of the wall element 44, to afford shoulders 71, these being in addition to the bottom marginal shoulder 66. In order to receive the modified wall element, the side margins 71 of the Venturi wall opening 46 will have to be modified in the casting of the Venturi casing section, such as to afford complementary shoulders (not shown) for lap-fit with the shoulders 71.

Fig. 5 discloses a modification in the manner of completing the primary Venturi wall. According to this view, the Venturi casing section is formed or cast as in the instance of the section of Fig. 1, to include a primary Venturi wall 72 which is here incomplete not only in one side thereof, affording the side opening 46, but at its upper end such that the wall terminates at 74 short of the Venturi entrance throat portion such as that indicated at 45 in Fig. 1. In this embodiment, the wall opening 46 is defined by side margins 75 and bottom margin 76 shouldered at 77, while the end terminal margin 74 is internally shouldered at 78.

Following drilling of the nozzle passage and assembly insertion of the nozzle element, the Venturi wall 72 is completed by a pre-formed member 80 having a wall element 81, the lower margin 82 of which is shouldered, and an annular wall part 83 shaped to provide a Venturi inlet throat 84. The annular wall part is undercut to afford a shouldered margin 85 extending from one side margin 86 of wall element 81 to the opposite side margin 87 of the latter. The member 80 is dimensioned for a press-fit with the Venturi wall 72, such that in assembly to the latter, the shoulders 82 and 85 have a firm lap-fit with the respective shoulders 77 and 78 of wall 72, while the side margins 86 and 87 are in pressed engagement with the side margins 75 of wall 72. The Venturi wall 72 thus is completed to afford a full Venturi passage having a defined entrance throat as provided by the annular wall part 83.

According to the present method of providing a primary Venturi and nozzle assembly of the

low angle nozzle type, the nozzle passage may be drilled with greater facility and greater accuracy as to the angular disposition thereof, while the nozzle element may be more easily inserted and accurately adjusted in place. Moreover, the present method avoids the disadvantages and difficulties including those hereinbefore noted, attending the older practice of drilling the nozzle passage from the outside of the body section, as through the outer wall 80 and inner wall 91 of the float chamber 18 (Fig. 1) and the mounting of plug seals at the drill openings in these walls.

Having now illustrated and described the invention, all modifications thereof in addition to the several embodiments herein disclosed, which come within the spirit and intended scope of the appended claims are contemplated.

I claim:

1. The method of making a carburetor Venturi section having a Venturi passage and a fuel nozzle therein, wherein the longitudinal axis of the nozzle in extension across the Venturi passage intersects the wall of the venturi, which comprises forming the Venturi section to have a Venturi-forming wall incomplete in its extent such as to leave an opening in one side thereof, forming a nozzle-receiving passage in the section by drilling through the Venturi wall with the drill extended through the side opening in the wall, thence arranging a nozzle element through the Venturi wall side opening and displacing the element into position in the nozzle-receiving passage of the section, and thereafter mounting a preformed wall element to the Venturi wall to close the side opening therein and complete the Venturi wall.

2. The method of making a carburetor Venturi section embodying a low angle fuel nozzle, which comprises forming the Venturi section to have a Venturi wall incomplete in its extent such as to leave an opening in one side thereof, forming a nozzle passage in the section extending through the Venturi wall at a point opposite the wall side opening by drilling through the wall with the drill extended through the wall side opening, inserting a nozzle element in the drilled passage, and thereafter press-fitting a preformed wall section to the incomplete Venturi wall to close the side opening thereof and complete the wall.

3. The method of making a carburetor Venturi section embodying a low angle fuel nozzle, which comprises forming the Venturi section to have a Venturi stack including a primary Venturi-forming wall incomplete in its extent such as to leave an opening in one side thereof, thence forming a nozzle passage in the section by drilling through the primary Venturi wall at a point opposite the wall side opening with the drill extended in and through such side opening, press-fitting a nozzle element in the drilled passage, and thereafter inserting and anchoring a preformed wall section in the side opening of the primary Venturi wall to close the opening and complete the wall.

4. The method of making a carburetor Venturi section embodying a low angle fuel nozzle, which comprises forming the Venturi section to have a Venturi wall incomplete in its extent such as to leave an opening in one side thereof, thence forming a nozzle passage in the section by drilling through the Venturi wall at a point opposite the side opening thereof, with the drill extended in and through such side opening, inserting a

nozzle element through said Venturi side opening and into the drilled passage, applying a preformed member having a wall element to the Venturi section with the wall element thereof in the side opening of the Venturi wall, to complete the latter, and thereafter anchoring the preformed member to the Venturi section.

5. The method of making a carburetor Venturi section embodying a low angle fuel nozzle, which comprises forming the Venturi section to have a primary Venturi wall incomplete in its extent, such as to leave an opening in one side thereof, with the wall margin defining the side opening having at least a portion thereof shouldered, thence forming a nozzle passage in the section by drilling through the Venturi wall at a point opposite the side opening with the drill extended in and through such side opening, inserting a fuel nozzle element in the drilled passage, and thereafter inserting a pre-formed wall section in the side opening of the Venturi wall in lap-fitted relation to the shouldered portion of the wall margin defining the opening, to close the opening and complete the primary Venturi wall.

6. The method of making a carburetor Venturi section embodying a low angle fuel nozzle, which comprises forming the Venturi section to have a primary Venturi wall incomplete in its extent such as to characterize the same by an opening in one side thereof, and by the absence of a wall portion defining the Venturi inlet throat, thence forming a nozzle passage in the Venturi section by drilling through the primary Venturi wall at a point opposite the side opening with the drill extended in and through such side opening, inserting a nozzle element in the drilled passage, and thereafter mounting a preformed wall section including a portion defining a Venturi inlet throat to the incomplete Venturi wall, thereby closing the side opening and providing the Venturi wall with an inlet throat.

7. The method of making a carburetor Venturi section embodying a low angle fuel nozzle, which comprises forming the Venturi section to have a Venturi-forming wall incomplete in its extent such as to leave an opening in one side thereof, thence forming a nozzle passage in the section by drilling through the Venturi wall at a point opposite the wall side opening, with the drill extended in and through such side opening, arranging a nozzle element in and through the Venturi wall side opening and thence displacing the nozzle into position in the drilled nozzle passage, and thereafter mounting a preformed wall element to the Venturi wall to close the side opening and complete the Venturi wall.

8. In a carburetor, a Venturi section providing therein a Venturi tube having a portion thereof which is incomplete in its circular extent, a wall element arranged on said tube in a position to complete said tube portion such as to afford a full circular extent thereof, and a fuel nozzle extending through the Venturi tube and directed such that its longitudinal axis in extension forwardly of the nozzle, intersects said wall element.

9. In a carburetor, a Venturi section providing therein a Venturi tube having a portion thereof which is incomplete in its circular extent, a wall element on said tube in a position to complete said tube portion such as to afford a full circular extent thereof, said wall element being marginally lap-fitted in assembly to the tube, and a fuel nozzle extending through said tube and directed such that its longitudinal axis

in extension forwardly of the nozzle, intersects said wall element.

10. In a carburetor, a Venturi section providing therein a Venturi tube having a portion thereof which is incomplete in its circular extent, a wall element on said tube in a position to complete said tube portion such as to afford a full circular extent thereof, a fuel nozzle extending through said tube and directed such that its longitudinal axis in extension forwardly of the nozzle, intersects said wall element, said wall element having a press-fit with said Venturi tube, and means securing the wall element to the Venturi section.

11. In a carburetor, a Venturi section providing therein a generally tubular member having a wall section which is incomplete in its circular extent, a sector-like wall element in lap-fitted assembly with said wall section and completing the same such as to afford a full circular extent thereof, said member being fixed to the Venturi section and defining with said wall element, a Venturi passage, and a fuel nozzle extending through the member and terminating in the Venturi passage, said nozzle being directed such that its longitudinal axis in extension forwardly of the nozzle, intersects said wall element.

12. In a carburetor, a Venturi section provid-

ing therein a generally tubular member having a wall section at one end which is incomplete in its circular extent, a sector-like wall element including an annulus thereon, in lap-fitted assembly with said wall section and completing the latter such as to afford a full circular extent thereof, said annulus being concentric with the end of said wall section, said member defining with said wall element and its annulus, a Venturi passage, and a fuel nozzle extending through the member into the Venturi passage, said nozzle being directed such that its longitudinal axis in extension forwardly of the nozzle, intersects said wall element insert.
